UNITED STATES PATENT OFFICE.

JOHN T. COLLINS, OF HARTFORD, CONNECTICUT, ASSIGNOR OF ONE-HALF
TO W. L. CURTISS, OF SAME PLACE.

AUTOMOBILE STREET-SWEEPER.

SPECIFICATION forming part of Letters Patent No. 669,683, dated March 12, 1901.

Application filed May 22, 1900. Serial No. 17,553. (No model.)

To all whom it may concern:

Be it known that I, JOHN T. COLLINS, a citizen of the United States of America, and a resident of Hartford, county of Hartford, and State of Connecticut, have invented certain new and useful Improvements in Automobile Street-Sweepers, of which the following is a specification.

This invention relates, generically, to sweepers of that class known as "street-sweepers," and is adapted to sweep and collect the dust and refuse from the street-surface, the propelling power being derived from any suitable motor carried on the sweeper, the motive agent of which can be any of the well-known types of machines, such as a steam-engine, electric storage system, gasoline or naphtha engine, or any of the other well-known power-generating devices.

The general object of my present invention is to furnish an improved automobile street-sweeper that is operated by power which may be of any well-known type.

A further object of my invention is to reduce the running expenses of the sweeper while the same is in operation upon the street by constructing and organizing the parts in such a manner that the manipulating-levers are within easy reach of the operator.

A further object of my invention is to provide simple and effective means for engaging or disengaging the brush-rotating mechanism or the propelling mechanism which drives the sweeper forward with the power-shaft, so that either of the two may be set in operation independently one of the other.

For a better comprehension of my invention attention is called to the accompanying drawings, forming a part of this specification, and wherein—

Figure 1 represents a side elevation of my improved street-sweeper, showing the motor which generates the power by which the sweeper is propelled, as a steam-engine, in connection with a steam-boiler, the smaller details of which are omitted. Fig. 2 is a plan view of that which is shown in Fig. 1. Fig. 3 is a cross-sectional end view taken on line 3-3 in the direction of the arrows 3, as seen in Fig. 2. Fig. 4 is a sectional plan view taken

on the median line of the counter-shaft and shows its coöperating mechanism, the same being drawn on an enlarged scale. Fig. 5 is an outside front view of the counter-shaft and its connection to the controlling and actuating mechanism, as shown in Fig. 4. Fig. 6 is an end elevation of the U-shaped traction-wheel axle drawn on a smaller scale.

Similar characters and numerals designate like parts in all the figures of the drawings.

In the preferred embodiment of my invention herein shown and described the automobile street-sweeper comprises a rectangular dust-receiving receptacle having an opening at the lower and rear end, two traction-wheels 65 mounted upon an axle 66 the central portion of which is bent in U shape and disposed transversely across the dust-receptacle, two steering-wheels mounted on the axle-carrier, which is pivoted on the forwardly-extending beams, 70 a suitable motor supported on the dust-receptacle, having a motor-shaft, means for connecting the motor-shaft with the counter-shaft, controlling mechanism for engaging and disengaging the brush-rotating mechanism 75 to revolve the brush in an opposite direction to the traction-wheels, driving and controlling mechanism operatively connecting the counter-shaft with the equalizing-case and driving mechanism to effectively engage 80 the traction-wheels.

The dust-receiving receptacle, which is designated in a general way by the numeral 10, is of a rectangular cross-section of rigid construction and adapted to receive the various 85 brackets for carrying the several operating and driving devices. The dust-receptacle has an opening 10^b at the rear and lower end to afford the operator a better view of the operation of the brush, and through which the brush 90 projects, permitting the same to be lowered, and at the front end it has connected thereto the gooseneck-shaped beam 11, to which is pivoted the steering-wheel-axle carrier 12, provided with the king-bolt 12^a, the purpose of 95 which will be described later, and this carrier is provided on the outer ends with the axles 13 and 14, adapted to receive the hubs of the steering-wheels 15, properly held to the axle in any well-known manner.

On the gooseneck - shaped beam 11 the sweeper is provided with the seat 16, and it is also adapted to receive and has journaled therein the steering-shaft 17, which carries at its upper end the hand-wheel 18 and at its lower end the sprocket-wheel 19, over which the chain 20 passes, the ends of which are connected to pins in the ends of the steering-head 21, which again is fastened to the king-bolt 12^a.

By the means just described any partial rotation imparted to the hand-wheel 18 by the operator will cause an angular deviation of the steering-wheel-axle carrier in relation to the central median line of the body of the sweeper, changing the angular relation of the traction-wheels and steering-wheel axles, and thereby directing the movement of the sweeper in a curved path or to turn a corner, as the case may be.

The traction-wheels 23 and 23^a are journaled on the axle 24, which is of U-shaped construction, as most clearly shown in Fig. 6, the two downwardly-projecting sides 24^a being fastened to the dust-receptacle 10, thereby sustaining the weight of the same and allowing the dust and dirt an unobstructed path as it is collected and swept into the receptacle. On the axle 24 and adjacent to each side of the receptacle are also mounted the brush-arms 25, the rearward extensions of which are provided with bearings 25^a, adapted to receive for rotation the brush-shaft 26, which projects through openings 10^a of the dust-receptacle, and to this shaft are rigidly fastened the brush 27 and the sprocket 28. The upward-extending branches of the brush-arms are adapted to receive the pins 29, pivotally jointing the connecting-rod 30 to these branches of the arms. The forward-extending ends of the connecting-rod are pivotally connected to the downwardly-dependant arms 31, fastened to the shaft 32, which is journaled in the oppositely-disposed bearings 33 and 34 at the front end of the dust-receptacle, and this shaft has also fastened thereto the manipulating-lever 35 directly to the right and in the rear of the seat 16.

By the means just described the operator from his seat 16 can elevate or lower the brush, as desired.

On the top of the dust-receptacle is mounted the motor, which may be of any well-known construction, for driving the motor-shaft 36, in this case represented as an engine 37, with its boiler 38. The motor-shaft is properly journaled in suitable bearings disposed on each side of the dust-receptacle and is provided with the sprocket 39, over which passes the chain 40 through proper openings in the top and front side of the receptacle to the sprocket 41, which is rigidly supported and held on the counter-shaft 42, which in this case forms a sleeve properly journaled in the brackets 43 and 44, held on the front side of the dust-

receptacle 10. The counter-shaft 42 has fastened thereto on the right-hand side of the operator by means of a spline and a feather 45, a clutch-coupling member 46, which is adapted to engage the clutch-coupling 47, each being provided with suitable engaging members having co-operating and corresponding notches of well-known construction. The clutch-coupling 47 is integral with the hub of the gear 48, journaled in the bracket 49, and engages the gear 50, which is journaled on the stud 51, securely fastened in the bracket 49, and that gear has securely held on its hub a sprocket 52.

By the means just described the direction of the rotation of the counter-shaft and the sprocket-wheel 52 is reversed. A sprocket-chain 53, passing over the sprocket-wheels 52 and 28, operatively connects and transmits the motion from the counter-shaft to the brush-shaft 26. As a convenient means for engaging and disengaging these shafts I have provided the lever 54, having a projection 55 engaging a groove of the clutch-coupling 46, and the same is pivoted by the pin 56 to a laterally-extending lug on the bracket 49, and whereby the clutch member 46 may be axially moved into or out of operative engagement with the clutch member 47, thereby controlling the rotation of the brush.

I will now describe the means whereby the sweeper is propelled forward.

As each traction-wheel is driven positively from one power-shaft, it is a well-known fact that a certain amount of slipping on one of the traction-wheels must occur when the sweeper turns a corner or moves in any curved path if no suitable means are interposed between the power-shaft and the traction-wheels. To obviate this slipping and to overcome the difficulties which arise therefrom, I have interposed between the counter-shaft 42 and the traction-wheels 23 the equalizing-case 57, constructed in halves, which supports the transversely-disposed cross-head 58, on which are adapted to revolve the oppositely-disposed planet-gears 59, meshing into the miters 60, which are rigidly fastened to the laterally-extending and axially-aligned shafts 61 and 62, respectively, each having a reduced end near the miters 60, which project into and are adapted to revolve in a properly-arranged bearing of the transversely-disposed cross-head 58. The equalizing-case 57 is provided on one side with the hub 63, which is journaled for rotation in the bracket 64, and at its other end is supplied with a clutch member 65, adapted to engage the notches of the clutch member 66, which is securely held against rotation on the counter-shaft 42 by a spline and a feather 67, and is thereby forced to revolve with the counter-shaft, but permitted a slight movement in the direction of the axis.

For engaging or disengaging the clutch members 65 and 66, which control the driv-

ing or propelling of the sweeper, I have arranged the lever 68, which is provided with the projection 69, the lower end of that lever being pivotally connected by the pin 70 to a laterally-extending lug 44^a of the bracket 44.

The shaft 61 carries on the outside and at the right of the operator the sprocket-wheel 72, and the axially-aligned shaft 62 carries on the outside the sprocket-wheel 73. Sprocket-chains 74 and 75 pass over the sprocket-wheels 72 and 73, respectively, and engage sprocket-wheels 76 and 77 on the hubs of the traction-wheels 23 and 23^a, and thereby effectively transfer a rotary motion from the axially-aligned shafts 61 and 62 to the traction-wheels 23 and 23^a, respectively.

The operation of the machine is as follows: Power which has been applied to the motor-shaft 36 by any of the well-known methods, and in this case by the engine-shaft, transfers a rotary motion, by means of the sprocket 39 and the chain 40, to the sprocket-wheel 41 and counter-shaft 42. When the sweeper is to be propelled forward, the operator engages the clutch member 66 with the clutch 65 of the equalizing-case 57, and the sweeper will be propelled forward. As long as the steering-wheels are in parallelism with the traction-wheels the sweeper will move in a straight line, and the planet-gears 59 will simply act as a dog between the miters 60, and therefore revolve the shafts 61 and 62 at a uniform speed. When the sweeper moves in a curved path or turns a corner to either side, the circumferential speed of the traction-wheels will vary and the planet-gears 59 will revolve slightly upon the axle of the transversely-disposed cross-head 58 in one direction or the other, according to the curved path in which the sweeper may be directed. The counter-shaft 42, which is also operatively engaged by the clutch-coupling 46, will, when engaged into the coupling 47, revolve the gear 48, thereby revolving the sprocket 52, which again revolves the brush-shaft, with the brush 27, in the opposite direction of the traction-wheels 23 and 23^a, and by lowering the brush to the desired extent by means of the lever 35 the dust will be swept into the dust-receiver 33 as the sweeper is propelled forward.

I claim—

1. In combination with an automobile street-sweeper, the dust-receptacle having the U-shaped traction-axle, a transversely-disposed opening in the lower rear end of the dust-receptacle, the forwardly-extending beam, the steering-wheel-axle carrier pivotally supported in the beam, the steering-wheels journaled on the carrier, the power-driven motor-shaft, the counter-shaft, means for operatively connecting the power-shaft with the counter-shaft, the traction-wheels, means for operatively connecting the traction-wheels to the counter-shaft, the brush, and means for driving the brush in an oppo-

site direction to the traction-wheels, substantially as described.

2. The combination with the dust-receiving receptacle having the forwardly-extending beam, the steering-wheel-axle carrier pivoted for oscillatory motion to the beam, steering-wheels journaled to the axle-carrier, the U-shaped traction-axle, traction-wheels journaled on the traction-axles, means for propelling the traction-wheels, the brush, means for revolving the brush in a reverse direction to the traction-wheels, and means for raising and lowering the brush, substantially as described.

3. In combination with an automobile street-sweeper, the dust-receiving receptacle, steering-wheels supporting substantially as described the forward end of the dust-receptacle, traction-wheels supporting substantially as described the rear end of the dust-receptacle, the power-driven motor-shaft supported for rotation on the top of the dust-receptacle, the counter-shaft, means for operatively connecting the motor-shaft with the counter-shaft, means for operatively connecting the counter-shaft with the traction-wheels to rotate both in the same direction, arms supporting the brush and pivoted to the traction-axle, means for operatively connecting the counter-shaft with the brush to rotate the same in a reverse direction, and means for engaging and disengaging the counter-shaft with the brush-rotating mechanism, substantially as described.

4. In combination with an automobile street-sweeper, the dust-receiving receptacle, steering-wheels supporting substantially as described the forward end of the dust-receptacle, traction-wheels supporting substantially as described the rear end of the dust-receptacle, the power-driven motor-shaft supported for rotation on the top of the dust-receptacle, the counter-shaft, means for operatively connecting the motor-shaft with the counter-shaft, means for operatively connecting the counter-shaft with the traction-wheels to rotate both in the same direction, arms supporting the brush and pivoted to the traction-axle, means for operatively connecting the counter-shaft with the brush to rotate the same in a reverse direction, means for raising and lowering the brush, and means for engaging and disengaging the counter-shaft with the brush-rotating mechanism, substantially as described.

5. In combination with an automobile street-sweeper, the dust-receiving receptacle, steering-wheels supporting substantially as described the forward end of the dust-receptacle, traction-wheels supporting substantially as described the rear end of the dust-receptacle, the power-driven motor-shaft supported for rotation on the top of the dust-receptacle, the counter-shaft, means for operatively connecting the motor-shaft with the

counter-shaft, means for operatively connecting the counter-shaft with the traction-wheels to rotate both in the same direction, arms supporting the brush and pivoted to the traction-
5 axle, means for operatively connecting the counter-shaft with the brush to rotate the same in a reverse direction, and means for engaging and disengaging the counter-shaft

with the traction-wheels, substantially as described.

Signed by me at Hartford, Connecticut, this 21st day of May, 1900.

JOHN T. COLLINS.
